OUTDOOR FIREPLACE

Hugh D. Carey, Syracuse, N. Y.

Application October 3, 1940, Serial No. 359,567

8 Claims. (Cl. 126—25)

This invention relates to an outdoor fireplace, or a cooking stove. Devices of this type have become quite popular and serve as a valuable adjunct to a home yard, or garden, permitting the cooking of food out of doors during the summer months of the year.

I have found that invariably each home owner incorporates his own structural ideas into the outdoor fireplace, with the result that many of them work inefficiently, or are ineffective for the purpose for which they are intended, and many are adversely affected by the outdoor elements and soon become an unsightly object rather than an attractive addition to the yard.

This invention has as an object an outdoor fireplace embodying a particularly economical structure which may be erected without the aid of skilled labor and when erected will serve efficiently, is attractive in appearance and particularly durable.

To these ends the invention contemplates a preformed stove unit in the nature of a sheet metal box embodying a particularly novel construction and which when suspended in a hollow vertically arranged masonry of simple construction serves as an efficient cooking unit.

The invention further contemplates an arrangement whereby a portion of the masonry serves as a combination warming closet or oven and a storage place for fuel, the construction as a whole presenting a neat and attractive appearance, all whereby the completed fireplace adds to the attractiveness of the surroundings.

The invention has as a further object the incorporation of means in the pre-formed stove unit for the efficient regulation for the draft of the fire under varying circumstances, and whereby the stove unit may be quickly and conveniently cleaned after use, and any accumulation of rain or snow is automatically disposed of without injury to the stove unit.

The invention consists in the novel features and in the combinations and constructions hereinafter set forth and claimed.

In describing this invention, reference is had to the accompanying drawings in which like characters designate corresponding parts in all the views.

Figure 1 is a front elevational view of a fireplace or outdoor cooking stove embodying my invention.

Figure 2 is a vertical sectional view taken on line 2—2, Figure 1.

Figure 3 is a top plane view.

Figure 4 is a top plan view of the stove unit with parts broken away and parts in section.

Figure 5 is a front elevational view of the stove unit.

Figure 6 is a top plan view of the fire grate.

The exterior construction of my fireplace con-

sists of a vertically arranged hollow masonry or chimney structure having a front wall 10, rear wall 11, and end walls 12. The masonry is here shown as formed of bricks and is preferably constructed upon a suitable base 13.

The stove unit consists of a rectangular sheet metal box open at the top and formed with an inclined bottom wall 14. In the construction shown, the front wall 15 of the box is of less height than the rear wall 17 and the end walls 18. The front wall 15 of the box and the front wall 10 of the masonry are of reduced height to permit the insertion of fuel without removing the cooking grill from the fireplace as will be hereinafter apparent. The walls of the box are formed with integral outwardly flaring flanges 20 adapted to overlie the upper edge of the masonry, or otherwise engage the same and serve to suspend the box therein. The box is dimensioned to be suspended in the masonry with the side walls of the box spaced slightly from the masonry to allow the expansion of the box while the fireplace is in use.

The bottom wall 14 of the box inclines downwardly and rearwardly, and the rear wall is provided with one or more apertures 21, and the rear wall 11 of the masonry is also formed with apertures arranged in register with the apertures 21. The apertures in the box are preferably in the nature of a short collar 22 on which a tubular projection 23 may be sleeved and in which is mounted a damper 24 movable upon a horizontal axis and being operable to effect regulation of the draft for the fire which is supported by a grate member 25 removably arranged upon brackets 26 secured to the inner surface of the front and rear walls 15, 17.

A cooking grill 28 is removably positioned on the top of the stove unit being supported by inwardly extending flanges 29 and a rod 30 extending transversely across the front of the box.

It will be apparent from the disclosure thus far that the stove unit, or fire box, can be economically formed from sheet metal, whereby it is available to the customer for a nominal price. The masonry can be readily constructed without the aid of skilled help inasmuch as it consists merely of a rectangular chimney structure not incorporating any offsets or other complicated construction. In addition to the relatively low material cost, the fireplace has the advantage of being particularly durable for outdoor locations.

The inclined bottom 14 and draft tubes 23 not only serve as a convenient means for regulating the draft but also serve to permit the escape of snow and rain from the interior of the stove unit, whereby the accumulation of moisture or ice, with the resultant damage to the fireplace, is prevented. Also, the grate 25 and grill 28 are readily removable and may be stored indoors

when the fireplace is not in use. The ash deposit through the openings in the grate 25 is accumulated on the bottom wall 14 and is conveniently removed by flushing out the interior of the stove unit with a hose, or pail of water.

Preferably, the front wall 10 of the masonry structure is formed with a sizeable aperture to receive a door frame 35 carrying a door 36 to provide access to the interior of the masonry below the stove unit. This compartment may be divided into an upper and lower compartment as by rods 37. I have found that the upper compartment serves as a dutch oven whereby food cooked on the grill 28 may be stored and kept warm until ready for use. The compartments below the rods 37 form a convenient storage place for charcoal or other fuel. I have found that the addition of one or two courses of brick above the grill 28 serves to prevent cross drafts from unnecessarily cooling the grill.

What I claim is:

1. An outdoor fireplace comprising a vertically arranged hollow masonry structure, the walls of which are vertically disposed and forming uniformly throughout its height, in a horizontal cross-section, a substantially closed structure having an open top, and a unitary metallic box-like structure supported entirely therein, fuel supporting means in the box-like structure and means to receive food to be cooked supported in the hollow masonry below the top thereof, the structure of the masonry being such that an opening between the top of one wall thereof and the food supporting means is provided, and through which opening fuel is inserted to be received on said fuel supporting means.

2. An outdoor fireplace comprising a vertically arranged hollow masonry structure open at its top and a unitary metallic open top box-like structure supported therein, the said masonry consisting of front, side and rear walls, the top of said front wall thereof being of lesser height than the tops of said side and rear walls, fuel supporting means in the box-like structure below the top of the masonry front wall, and means to receive and support food to be cooked mounted in the hollow masonry below the top of the side and rear walls of the masonry and above the top of the said masonry front wall thereby providing an opening between the top of the said front wall and the food supporting means and through which opening fuel may be inserted to be received on said fuel supporting means and whereby the said side and rear walls also prevent undue drafts of air that are detrimental to combustion as well as to the food that is being cooked.

3. A fireplace as defined in and by claim 2 and wherein the said box-like structure comprises front, side and rear walls and a bottom, the said rear wall having an opening therein adjacent the said bottom, means to open and close the said opening in the rear wall of the box-like structure and said means when open permitting debris to be flushed from the said box-like structure out through the said opening.

4. An outdoor fireplace comprising a vertically arranged hollow masonry structure open at its top and a sheet metal box-like structure also open at its top supported therein, by means of outwardly extending integral flanges which flanges extend into the said masonry, the said masonry consisting of front, side and rear walls, the top of said front wall thereof being of lesser

height than the tops of said side and rear walls all of which are of the same height, a fuel grate in the box-like structure below the top of the masonry front wall, and a grill to receive and support food to be cooked mounted in the hollow masonry below the top of the side and rear walls of the masonry and above the top of the said masonry front wall thereby providing an opening between the top of the said front wall and the grill and through which opening fuel may be inserted to be received on said grate and whereby the said side and rear walls also prevent undue drafts of air that are detrimental to combustion as well as to the food that is being cooked.

5. A fireplace as defined in and by claim 4 and wherein the said box-like structure comprises front, side and rear walls and a bottom, the said bottom being inclined downwardly from the front wall to the said rear wall of the box-like structure, and the said rear wall of the box-like structure having an opening therein adjacent the said bottom, pivoted means for opening and closing the said opening, and said pivoted means when open permitting debris to be flushed from the box-like structure out through the said opening.

6. An outdoor fireplace comprising a vertically arranged hollow masonry structure open at its top and a sheet metal open top box-like structure consisting of integral front, side and rear walls, and an inclined bottom supported therein by means of outwardly extending flanges integral with the said walls thereof which flanges extend into the said masonry, and the said front wall of the box-like structure being of lesser height than the side and rear walls thereof, the said masonry consisting of front, side and rear walls, the top of said front wall thereof being of lesser height than the tops of said side and rear walls, and the disposition of the box-like structure 30 within the hollow masonry being such that the top of the front wall thereof is below the top of the front wall of the masonry and the tops of the side and rear walls thereof are below the side and rear walls of the masonry, fuel grate means 35 in the box-like structure below the top of the masonry front wall and below the top of the front wall of the box-like structure, and a grill means to receive and support food to be cooked mounted in the hollow masonry below the top of the side and rear walls of the masonry and above the top of the said masonry front wall thereby providing an opening between the top of the said front wall of the masonry and the grill and through which opening fuel may be inserted to be received on said grate and whereby the said side and rear walls of the masonry structure also prevent undue drafts of air that are detrimental to combustion as well as to the food that is being cooked.

7. A fireplace as defined in and by claim 6 wherein the said rear wall of the box-like structure is provided with an opening adjacent the said inclined bottom, pivoted means for opening and closing the said opening in the box-like structure, and said pivoted means when open permitting debris to be removed from the box-like structure out through the said opening.

8. A fireplace as defined in and by claim 6 wherein the said side walls of the box-like structure are in spaced relation to the said side walls of the masonry structure thereby permitting expansion of box-like structure.

HUGH D. CAREY.
